APPARATUS FOR ZONE REFINING
ELONGATED BODIES OF METAL

James O. Hinkle, Emmaus, and Robert K. Miller and Jack J. Monahan, Allentown, Pa., assignors to Western Electric Company, Incorporated, New York, N.Y., a corporation of New York

Filed Apr. 4, 1961, Ser. No. 100,677
17 Claims. (Cl. 13—1)

This invention relates to apparatus for zone refining elongated bodies of metal, particularly elongated silicon bodies.

Silicon wafers used in the manufacture of semi-conductor devices are produced from silicon rods, but in order that the semi-conductor devices may function most efficiently, the rods from which the silicon wafers are produced, must be of sufficient purity.

An object of the present invention is an apparatus which is highly efficient in zone refining elongated bodies of metal.

In accordance with the object, the apparatus comprises a vacuum chamber in which an induction heating coil is mounted and a chuck for supporting an elongated body of metal is mounted on a spindle disposed in axial alignment with the coil, while means is provided to impart movement to the spindle to move the body of metal at a predetermined speed through the coil.

More specifically, the apparatus includes spaced chucks for connection with both ends of the elongated body of metal, that is, chucks having individual moving means including spindles for supporting the chucks, motors for rotating the spindles simultaneously, a main drive connected to both moving means, to move the elongated body of metal at a predetermined speed relative to the heating coil with associate drives for the moving means interposed between the main drive and the moving means, to cause variation in the driving speed of each moving means, to result in uniform thinning or broadening the elongated body of metal. The associate drives are connected to the main drive through differential units adapted to condition the main drive, to move the spindles at like known speeds when the associate drives are de-energized and to condition the main drive through either or both differential units to drive the spindles at greater or slower speeds selectively to control the movement of the elongated body of metal through the coil to create controlled variations in the size of the body of metal.

Other objects and advantages will be apparent from the following detailed description when considered in conjunction with the accompanying drawings wherein:

FIG. 1 is a side elevational view of a portion of the apparatus including the main and associate drives;

FIG. 2 is a front elevational view of an upper portion of the apparatus;

FIG. 3 is a front elevational view shown partially in section of a lower portion of the apparatus;

FIG. 4 is a front elevational view of the structure shown in 4—4 of FIG. 1 with the associate drives removed;

FIG. 5 illustrates the necessary positioning of FIGS. 2, 3, and 4 to show the complete apparatus;

FIG. 6 is a schematic isometric view of one of the differential units; and

FIGS. 7, 8, 9, and 10 are schematic illustrations of the actions of the apparatus for movement of the elongated body of metal relative to the heating coil.

After FIGS. 2, 3, and 4 have been positioned to illustrate the complete apparatus, it will be noted that a central portion of the apparatus includes a vacuum chamber 26 provided with a door 21 secured in place by clamps

2

22 and removed during unloading and loading of the work. A heat induction or radio frequency coil 23 is mounted centrally of the vacuum chamber and is of a contour to receive an elongated body of metal 24.

In the present instance, this is a silicon body $\frac{1}{2}$ " in diameter and 1' in length. Hollow chucks 25 and 26 are adapted to receive the ends of the body 24 and are provided with suitable means such as set screws 27 and 28 to secure the ends of the work in the chucks. The chucks 25 and 26 are provided with identical moving means indicated generally at 29 and 30. Any description of the moving means 30 will apply to both units.

In the FIG. 3 portion of the apparatus, the chuck 26 is fixedly mounted on the upper end of a spindle 31 which extends freely through a hollow threaded shaft 32 and through an outer sleeve 33 where its outer end is connected to a motor 34 of a type adapted to rotate its spindle at a definite slow speed simultaneously with the motor 34 of the moving means 29 so that both spindles 31 of the moving means 29 and 30 will be rotated simultaneously at the same speeds and in the same direction. The purpose of the motor 34 is to rotate the work or the elongated body of metal in the coil 23 to assure uniform heating of the successive floating zones of the body of metal moving through the coil 23.

The outer sleeve 33 has a nut or internally threaded element 36 mounted in the end thereof opposite the end supporting the motor 34 for operative engagement with the threaded shaft 32. Furthermore, the outer sleeve 33 is positioned to move in a hollow portion 37 of a housing 38 which is fixed to a casing 39, the latter being secured to a bracket 40 which supports the vacuum chamber and both moving means 29 and 30. The sleeve 33 supports a projection 33' positioned to ride in an elongated slot 38' of the housing 38 to hold the sleeve against rotation. A cam 41 mounted on each outer sleeve 33 is positioned to engage series of switches 42, 43, 44, 45, 46, 47, 48, and 49 which serve in the operation of the apparatus, mainly to control movements of the chucks 25 and 26 and to assure stopping of the movements thereof prior to interference with the coil 23 or the supporting structures at the opposite ends of the vacuum chamber.

Each moving means 29 and 30 has a worm gear 51 fixedly mounted on its threaded shaft 32 and supported by bearings 52 in the casing 39, and 53 in the housing 38. A worm 54 is rotatably mounted in each casing 39 and interengages its respective worm gear 51. Each worm 54 is provided with a shaft 55 coupled at 56 to a shaft 57. In the present illustration, the shafts 57 may be connected to either a main drive or motor 58 or a rapid return drive or motor 59 through their respective clutches 60 and 61. Helical gears 62 mounted on the shafts 57 are connected to helical gears 63 mounted on shafts 64 of the output portions of clutches 61. The shafts 57 extend to and constitute the output shafts of clutches 60.

At this point, it should be understood that suitable electrical circuits may be provided for the main and return drives 58 and 59 and that these circuits may have the conventional electrical controls for the clutches 60 and 61, which may be suitable magnetic clutches, so that only one of the motors 58 and 59 may be energized at one time, that when that motor is energized, its respective clutch will be engaged and when that motor is de-energized, its respective clutch will be dis-engaged. The rapid speed return drive or motor 59 has shafts 65 and 66 extending from opposite ends thereof to the input portions of their clutches 61.

Attention is now directed to FIGS. 1 and 3 illustrating the main drive or motor 58 having shafts 70 extending

from opposite ends thereof, these shafts being connected at 70° to input shafts 67 of differential units 71. The differential units are identical with the exception that they extend in opposite directions. The differential unit, shown in FIG. 6, illustrates the input shaft 67 extending through a hollow shaft 72 and into a cage of the differential where it has a gear 73 mounted thereon. The cage of the differential is composed of head portions 74 secured together and supported in their relative positions by a plurality of rods or spindles 75. An output shaft 77 of the differential has a gear 78, similar in size to the gear 73, mounted on its inner end. A pair of gears 79 and 80, mounted on a hollow shaft 81, is rotatably supported on one of the rods 75 while another pair of gears 82 and 83, mounted on a hollow shaft 84, is rotatably supported on another of the rods 75. The pairs of gears are positioned and maintained in these respective positions so that gear 79 will interengage gear 73, gears 80 and 82 will interengage each other, and gear 83 will interengage the gear 78. The cage fixed to the hollow shaft 72 is under the control of a beveled gear 85 which is fixed to the hollow shaft and interengages a beveled gear 86. The output shafts 77 are connected through couplings 88 to input shafts 90 of speed reducing units 91.

The beveled gears 86 are mounted on output shafts 92 of speed reducing units 93 of auxiliary drives or motors 94 and 95. The motors 94 and 95 are included in circuits from line 96, through their individual switches 97 and 98. The switches, schematically illustrated in FIG. 1, are adapted to de-energize either associate drive 94 or 95, to drive these motors simultaneously in like or reverse directions and through the aid of additional controls, such as potentiometers 99 and 100, the speeds of the associate drives may be identical or variable.

Operation

Through the controls of the associate drives 94 and 95, the chucks 25 and 26 may be located relative to each other in the vacuum chamber so that after the cover 21 has been removed and the holding means or set screws 27 and 28 have been loosened, the chucks may be moved relative to each other to permit removal of a refined body of metal 24 and the insertion of another to be refined as illustrated, for example, in FIG. 10. Through this or other suitable control means, the chucks 25 and 26 may be moved toward each other during the mounting of a new workpiece in the chucks and after the ends thereof in the chucks, the chucks with the workpiece may be located at the starting position shown in FIGS. 2 and 7.

If desired, during the first series of movements of the work through the coil in the feeding direction which, in the present instance, is upwardly, the control means may be set at the speed desired. The upward or treating movement of the apparatus through the main drive is variable between .0001 and .0015 of an inch per second but is set at the selected speed. As the work moves relative to the coil, there is produced a floating zone in the work in the area of the coil where the metal in this area is molten and is supported by surface tension. Therefore, if it is desirable to bring about thinning or broadening of the contour of the work or the bar of metal, it is necessary that this be done in such a manner that the thinning or broadening effects may be produced by the minute controlling of varying speeds extending from the main drive or motor 58 through to the worms 54, the worm gears 51, the threaded shafts 32, the internally threaded elements 36, the external sleeves 33, and back through the spindles 31 to the chucks 25 and 26. As an example, with the associate drives 94 and 95 de-energized, they will function to hold the cages of their differentials 71 stationary and, as a result, a setting of a control for the main drive to bring about 10 revolutions per minute of the input shafts 67, will result in 10 revolutions of the output shafts 77 and through the speed reducing units 91, the clutches 69 and onto the moving means 29 and 30, to

move the chucks 25 and 26 in unison so that they will carry out their separate functions of supporting the upper and lower ends of the work with the floating zone of the work continuing as the work moves through the heating coil 23.

As another example, if either or both associate drives 94 and 95 should rotate its cage of its respective differential 71 in the opposite direction of the input shaft one revolution per minute, there will be 12 revolutions per minute of the output shaft 77 to every 10 revolutions per minute of the input shaft 67. In following this example, it is apparent that the de-energization of one of the associate power units 94 or 95 will cause it to hold its differential cage stationary while the other is rotating its differential cage one revolution per minute in the opposite direction of its input shaft, to cause a constant known variation in the speeds of the moving means 29 and 30 to bring about a thinning result to the work.

As a further example, if either associate drive 94 or 95 should cause rotation of its differential cage one revolution per minute in the same direction as the direction of rotation of the input shaft, the rotation of the output shaft 77 would be only 8 revolutions per minute as compared to the 10 revolutions per minute of its input shaft 67. This illustrates the possibility of moving the work at a controlled slower rate when both associate drives 94 and 95 are moving their differential cages at like speeds to produce varied speeds of longitudinal movement of the work through the heating coil, and if one of the associate drives should be held de-energized to hold its differential cage stationary, while the other associate drive brings about a slower drive for the output shaft 77, then there will result a broadening of the work through the successive floating zones moving through the coil 33. Also, these varying speeds may be accentuated by the driving of the motors in directions to cause faster results in the thinning and broadening actions. Regardless of how the thinning and broadening actions are produced and the extremity of their variations, these changes occur gradually during the slow advancement of the floating zone and during any one, any number or all the repeated movements of the body of metal through the coil to produce a refined body of metal of a predetermined cross-sectional contour throughout its length.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. An apparatus for zone refining an elongated body of metal comprising an elongated vacuum chamber, aligned chucks disposed in the vacuum chamber for receiving opposing ends of a body of metal, means to secure the ends of the body of metal in the chucks, an induction heating coil mounted in the vacuum chamber concentric with the body of metal, axially aligned spindles for the chucks extending through opposing ends of the vacuum and fixed to their respective chucks, separate means to move the spindles with their chucks axially to move the body of metal in one direction from a starting position through the coil at a predetermined speed, a forward drive adapted for connection with the separate moving means, and an energizable auxiliary drive operatively connected intermediate the forward drive and one of the moving means to vary the speed of axial movement of its spindle and chuck relative to the other spindle and chuck.
2. An apparatus according to claim 1 in which the operative connection between the forward drive and the one of the moving means is a differential through which the speed of the moving means depends on the energization and de-energization of the auxiliary drive.
3. An apparatus for refining an elongated body of

metal comprising a vacuum chamber, an induction heating coil mounted at a starting position in the chamber, a spindle extending into the chamber in axial alignment with the coil, a chuck mounted on an inner end of the spindle to receive one end of the body of metal, moving means for the spindle to cause axial movement of the body of metal relative to the coil, a main drive for the moving means, a differential having an input shaft operatively connected to the main drive, an output shaft operatively connected to the moving means, a cage rotatable axially of the shafts and intermediate gears movable with the cage and operatively connecting the shafts, and an auxiliary drive operatively connected to the cage of the differential to control the effect of the main drive to cause the moving means to move the spindle at variable speeds.

4. An apparatus according to claim 3 in which means is adapted to cause the auxiliary drive to be inactive to thereby hold the cradle against rotation so that the output shaft will be driven at the same speed as the input shaft.

5. An apparatus according to claim 3 in which means is adapted to cause the auxiliary drive to rotate the cage in one direction so that the output shaft will be driven at a faster speed than the speed of the input shaft.

6. An apparatus according to claim 3 in which means is adapted to cause the auxiliary drive to rotate the cage in one direction so that the output shaft will be driven at a slower speed than the speed of the input shaft.

7. An apparatus according to claim 1 in which a reverse drive is adapted for connection with the separate moving means when the forward is disconnected therefrom to cause the spindles and chucks to return to their starting positions with the body of metal at a more rapid rate of speed.

8. An apparatus for zone refining an elongated body of metal comprising an elongated vacuum chamber, an induction heating coil mounted at a refining position in the chamber, aligned chucks for gripping opposing ends of the body of metal aligned with the coil on opposing sides thereof in the chamber, axially aligned spindles extending through opposing ends of the chamber and having their inner ends fixed to their respective chucks, separate means operable to move the spindles axially with their chucks from starting positions to move the body of metal through the coil, a main drive adapted through clutch connections with the separate moving means to move the spindles axially simultaneously to keep the chucks spaced the same distances apart during refining of the body by melting successive portions thereof during the intervals they are located in the refining position.

9. An apparatus according to claim 8 in which a rapid return drive is operable through clutch connections with the separate moving means when the clutch connections for the main drive are rendered ineffective to rapidly return the chucks to their starting positions.

5 10. An apparatus according to claim 8 in which the main drive is a main motor having two shafts, differentials having input shafts connected respectively to the shafts of the main motor, output shafts operatively connected to their respective separate moving means and cages having gears operatively connecting their input and output shafts, and auxiliary motors operatively connected respectively to the cages of the differentials.

15 11. An apparatus according to claim 10 in which means is operable to cause de-energization of the auxiliary motors to cause them to hold the differential cages stationary so that the speeds of the output shafts will equal the speeds of the input shafts.

12. An apparatus according to claim 10 in which means are operable to cause energization of the auxiliary motors to cause rotation of the cages to cause the output shafts to be driven at faster speeds than the input shafts.

20 13. An apparatus according to claim 10 in which means are operable to cause energization of the auxiliary motors to cause rotation of the cages to cause the output shafts to be driven at slower speeds than the input shafts.

25 14. An apparatus according to claim 10 in which means are operable to cause energization of one of the auxiliary motors in a given direction to cause movement of its chuck relative to the other chuck to cause variation in the thickness of the body of metal.

30 15. An apparatus according to claim 10 in which means are operable to cause energization of either auxiliary motor in either reversible directions to cause advancement of the chucks at predetermined variable speeds to control predetermined variations in the thickness of the bar of metal.

35 16. An apparatus according to claim 10 in which means are actuatable to energize the auxiliary motors at like and variable speeds to drive the output shafts at like and variable speeds to control the speeds of movement of the chucks.

40 17. An apparatus according to claim 10 in which each auxiliary motor is provided with switch means to de-energize or energize in either direction, and means to vary the speed of rotation of each auxiliary motor to vary the speed of the differential cage and the output shaft thereof.
